UNITED STATES PATENT OFFICE.

THOMAS L. DUNBAR, OF WATERTOWN, NEW YORK, ASSIGNOR TO CHEMIPULP PROCESS, INCORPORATED, OF JEFFERSON COUNTY, NEW YORK, A CORPORATION OF NEW YORK.

PROCESS AND APPARATUS FOR TREATING FIBROUS MATERIALS FOR PULPING PURPOSES.

Application filed April 22, 1927. Serial No. 185,775.

One of the objects of the invention is to provide a process and apparatus which will be equally as efficient in the cooking of sulphate or soda pulp.

5 Another object is to furnish a process and apparatus adapted to conserve the liquor drained from the digester for reuse and conditioning, and to eliminate one washing cycle in the diffuser or blow tank, thereby saving time, chemicals and heat units.

10 A further object is to provide a process and apparatus which allows the digester being used not only as a cooking device, but as a recovery device in a novel manner.

15 With the foregoing objects outlined and with other objects in view which will appear as the description proceeds, the invention consists in the novel features and steps hereinafter described in detail, illustrated in 20 the accompanying drawing and more particularly pointed out in the appended claims.

In the accompanying drawing, a diagrammatic view of the improved apparatus is shown.

25 Referring to the drawing, 1 designates a digester, 2 an equalizing tank, and 3 an accumulator. These are the main elements of the apparatus, and liquids and gases may be circulated from one to the other, by means 30 now to be described.

The upper portion of the digester is connected to a pipe 4, provided with a control valve 5, and connected to a cross-shaped fitting 6. Another pipe 7 connects the top of 35 the digester to this fitting and is provided with a control valve 8. The fitting 6 is connected to the bottom of the equalizing tank by a conduit 9 having a control valve 10.

A gravity feed pipe 11 having a valve 12, 40 connects the equalizing tank to the intake 13 of a pump 14, and a by-pass pipe 15 having a valve 16, connects the pipe 11 to the fitting 6.

The outlet 17 of the pump is connected to 45 a pipe 18 that leads to a strainer fitting 19 at the bottom of the digester.

Steam is fed into the bottom of the digester either through intakes 20 or a pipe 21 fitted with a valve 22, the parts 20 and 21 50 leading into the strainer fitting.

Considering the apparatus thus far described, when used in carrying out the sulphite process, it may be stated that for cook-

ing purposes, the digester is substantially filled with chips and acid, and is properly sealed against escape of heat or acid fumes. 55 Steam is then introduced through the intakes 20, and this steam acts as a circulating medium for the acid through the chips, and at the same time, it builds up the temperature and pressure within the digester.

When the temperature has reached approximately 212° F., the valves 5, 8, 10 and 12 are opened, and the pump 14 is started. 60 The pump draws the acid which has increased in volume, by means of steam condensation, through pipes 4 and 7, through pipe 9, equalizing tank 2, and pipe 11, into the pump, and then forces the same through the pipe 18 into the bottom of the digester, 65 thus circulating the acid through the digester. Meanwhile, the steam entering the digester continues to condense and adds liquid volume, so that eventually the liquor in the equalizing tank reaches the liquor line 70 or level 23. At this time, a valve 24 in a liquor overflow pipe 25, may be opened and the liquor will flow into the "Semco" trap 26. When the trap is full of liquid, the automatic valve with which such traps are 75 equipped, opens and permits gas to flow through a pipe 27 into the trap, and by its pressure to force the liquor through a pipe 28 into the top of the accumulator 3.

The gas for this purpose is taken from 80 the upper end of the equalizing tank through a pipe 29, and may be controlled by a valve 30.

As the gas accumulating in tank 2 is greater in amount than that needed to operate the trap, such gas is permitted normally to flow through a pipe 31 having a control valve 32. Pipe 31 leads the gas to a gas siphon 33 which receives liquid forced by the pump up from pipe 18, through pipe 34. The gas and liquid are, of course, thoroughly mixed in the gas siphon, and this permits the liquid to absorb the gas; this mixture flowing by way of pipe 35 into the intake of the pump and being circulated by 100 the latter through the digester, thereby enabling the use of a weaker cooking liquor, by reason of the fact that the gases are retained in circulation instead of being vented from the digester into the usual recovery 105 tank.

This arrangement allows not only for the digester being used as a cooking means, but as a recovering device in a novel manner.

The pump can be located, if desired at 5 any point below the level shown; preferably it is positioned at the bottom of the digester, but the equalizing tank is preferably, though not necessarily, located at the top of the digester.

10 From the foregoing, it will be appreciated that when the valves are properly set, at the beginning of operation, the liquor may be simply circulated through the digester by the pump 14. However, as the volume of 15 liquid increases, due to the addition of the condensate from the steam, this excess will be taken care of by the equalizing tank and the trap 26. Furthermore, as the gas is generated, it is mixed with liquor, re-absorbed and recirculated through the digester, so that the latter functions as a recovery device.

Due to this system, the heat given off by the gas in its absorption by the liquor is 25 imparted to the latter, so that heat units are conserved.

Before the volume has become sufficient to necessitate the use of the equalizing tank, the liquor drawn by the pump 14 through 30 the pipes 4 and 7 may be fed through the by-pass pipe 15 instead of through the equalizing tank.

After the volume of liquor increases to a point where it cannot be handled by the 35 digester and equalizing tank, the excess of liquor can be drained off into the accumulator. For this purpose, the digester is provided with three valved outlets 36, 37, and 38 arranged respectively at its top, intermediate portion and bottom, and all communicating with a pipe 39 having valves 40 and 41. This pipe communicates at its lower end with a conduit 42 which leads to the lower portion of the accumulator. Due 40 to this arrangement, excess liquor may be passed either from the top, intermediate portion or bottom of the digester by gravity, into the accumulator.

Another conduit 43 having a control valve 50 44 connects the other end of the pipe 39 to the accumulator, and may be used to conduct either gas or liquor from the digester to the accumulator, or vice versa.

Liquor from the accumulator may be 55 forced by a pump 45 through a valved conduit 46 and a pipe 47 into the bottom of the digester, or the liquor from the pump may be by-passed through valved pipe 48 into the pipe 39, which conveys it into the upper portion of the digester.

The pump 45 is preferably reversible, so as to act as a circulating means for liquor from the accumulator to the digester, or from the digester to the accumulator.

60 It may be stated at this point, that the

accumulator is used to accumulate acid, alkaline liquids, or water, and is used as a medium for the recovery of gases and heat units. In this connection, it may be noted that liquor flowing through the pipe 28 may be 70 commingled with gas passing through the pipe 43, within the accumulator for the purpose of adding the heat units of the gas to such liquor, and for reabsorbing the gas.

The digester is provided with a drain pipe 75 49 leading to a sewer or a storage tank.

The application of the foregoing arrangement is equally as efficient in the cooking of sulphate or soda pulp. The general arrangement in cooking either of the sulphate or soda pulps would be somewhat different than in the cooking of sulphite, in that circulating pump 45 would transfer the liquor showering the uncovered chips in the digester, since it is not necessary in the soda or sulphate industry; to entirely cover the chips with a liquor solution. When the apparatus is used for the latter purpose, after the chips have started to pulp, the liquor is drawn from the digester back into 80 the accumulator, in excess of that which is pumped into the digester, thus allowing the latter to be practically drained free of liquor at the end of the cooking. At this time, weak liquor is pumped into the top of the 85 digester, thus giving the first washing effect in the digester instead of in diffusers or blow tanks, as heretofore, and rebuilding the pressure, in order to obtain enough pressure to blow the contents out of the digester. 90 This weak liquor also gives the pulp a pre-washing, whereas in the old method the contents of the digester is blown into a diffuser, and the pulp so blown carries with it the liquor with which the same has been cooked. 95 The liquor which has been drawn back into the accumulator is ready for reuse or reconditioning.

As before stated, the purpose of this process is to not only better conserve the liquor 100 drained from the digester for reuse and conditioning, but to eliminate one washing cycle in the diffuser or blow tank, thereby saving time, chemicals and heat units.

It is believed that the foregoing description, when read in connection with the accompanying drawing, will enable those skilled in the art to practice this invention, and it is obvious that changes may be made in the details set forth without departing 115 from the spirit of the invention as expressed in the claims.

What is claimed and desired to be secured by Letters Patent is:

1. In a chemical pulping process, chemically digesting fibrous material while introducing steam into the same, permitting the steam to condense and mix with the liquor used for digesting purposes, continuously circulating the mixed liquids through said 120

- fibrous material, and after the mixture reaches a predetermined volume, directing the excess of the mixed liquid into an accumulator.
5. 2. In a process as claimed in claim 1, withdrawing liquor and gas from the sphere of digestion after the liquor reaches a temperature of about 212° F., mixing the same and causing the liquid to absorb the gas, and then circulating the gas enriched liquid through the sphere of digestion.
10. 3. In a chemical pulping process, digesting fibrous material with chemical liquor under super-atmospheric temperature and pressure until the liquor reaches a temperature of about 200° F., then continuously withdrawing chemical liquor and gas from the sphere of digestion, commingling said liquor and gas and causing said liquor to absorb the gas, and immediately returning the gas enriched liquor to the sphere of digestion.
15. 4. In a chemical pulping process, digesting fibrous material with chemical liquor in the digester, mixing steam with said liquor in a digester and thus heating the liquor to substantially 200° F., preventing liquor from leaving the digester until the liquor has been heated to substantially 200° F., and then gradually and continuously withdrawing said liquor and gas from the sphere of digestion, mixing the withdrawn liquor and gas to cause the liquor to absorb the gas, and the latter to heat the liquor, and immediately returning the gas enriched liquor to the sphere of digestion.
20. 5. In a chemical pulping process, digesting fibrous material in a digester with chemical liquor and steam, adding condensate from the steam to the liquor until a predetermined volume is reached, permitting excess liquid from this mixture to gradually accumulate in a separate chamber, and utilizing gas created during the digestion to discharge said accumulated mixed liquid into a third chamber.
25. 6. In a chemical pulping process, digesting fibrous material with chemical liquor and steam, gradually draining the liquor from the fibrous material during the cooking, so that the liquor is completely drained at the end of a cook, then introducing a weak liquor solution from some other source into the drained fibrous material to rebuild the pressure sufficiently to discharge the fibrous material from the chamber in which it was cooked.
30. 7. In a chemical pulping process, digesting fibrous material in a chamber with chemical liquor and steam, gradually draining the liquor from the digester during the cooking so that the liquor is completely drained at the end of a cook and thus leaving the fibrous material practically free of liquor, then pumping a weak liquor solution into the drained fibrous material and thus rebuilding the pressure sufficiently to discharge the contents out of the digester, and utilizing said weak liquor to give the pulp a prewashing.
35. 8. An apparatus of the class described, including a digester, an equalizing tank, a circulating pump, pipes connecting opposite ends of the digester to the pump, pipes connecting one of the last mentioned pipes to the equalizing tank, and valves in said pipes to permit liquid from the digester to be circulated by the pump through the equalizing tank or directly through the pump and digester.
40. 9. In an apparatus of the character described, a digester, a pump, pipes connecting the digester to the pump to permit the latter to circulate liquid through the digester, a mixing device, a gas conveying conduit connected to the mixing device, another conduit connecting one of said pipes to the mixing device for leading liquid from the digester into the mixing device, and a passageway connecting the mixing device to the intake of the pump.
45. 10. In an apparatus of the class described, a digester, an equalizing tank, a pump, pipes connecting one end of the digester to the intake of the pump, another pipe connecting the outlet of the pump to the other end of the digester, and valved pipes connecting the equalizing tank to certain of the other pipes to permit the pump to simultaneously circulate liquid through the digester and equalizing tank.
50. 11. In an apparatus of the character described, a digester, an equalizing tank, a pump, a conduit connecting one end of the digester to the equalizing tank, another conduit connecting the equalizing tank to the pump, and a third conduit connecting the pump to the other end of the digester.
55. 12. An apparatus of the class described, including a digester, an equalizing tank, a pump, a hollow fitting, valved pipes connecting said fitting respectively to the intake of the pump, the equalizing tank and the digester, a valved pipe connecting the equalizing tank to the intake of the pump, and another valved pipe connecting the outlet of the pump to the digester.
60. 13. An apparatus of the class described, including a digester, an equalizing tank, a pump, and valved pipes connecting the digester, equalizing tank and pump, and arranged to permit the pump to circulate liquor through the digester alone or simultaneously through the digester and equalizing tank.
65. 14. An apparatus as claimed in claim 13, including a gas siphon, a gas conducting conduit connecting the upper portion of the equalizing tank to said gas siphon, another conduit connecting one of said pipes to the

- gas siphon for conducting liquor from said pipe to the gas siphon, and a third conduit placing the outlet of the gas siphon into communication with the intake of the pump.
15. An apparatus as claimed in claim 13, including a trap, a liquor overflow pipe placing the equalizing tank in communication with the trap, and means for conveying gas from the top of the equalizing tank to said trap for blowing liquid out of said trap.
16. An apparatus as claimed in claim 13, including an accumulator, a trap, liquor conducting pipes placing the equalizing tank in communication with the trap, and the trap in communication with the accumulator, and a gas conducting line placing the upper portion of the equalizing tank in communication with the trap for use in blowing liquor from the trap into the accumulator.
17. In an apparatus of the class described, a digester, an accumulator, a pump, a pipe connecting one end of the digester with one end of the accumulator, another pipe placing one end of the digester in communication with the accumulator, a third pipe placing said pipes in communication, branch pipes connecting the last mentioned pipe to the digester at different elevations, another pipe placing the third pipe in communication with the accumulator, said pump being interposed in one of said pipes.
18. In a chemical pulping process, chemically digesting fibrous material in a digester while introducing steam into the digester, permitting the steam to condense and mix with the liquor used for digesting purposes, gradually releasing heated mixed liquids from the digester after the liquids have reached a predetermined temperature, circulating the mixed liquids thus released exteriorly of the digester, and then returning a portion of the same through said fibrous
- material, and after the mixture reaches a predetermined volume, directing the excess of the mixed liquids into an accumulator.
19. In a chemical pulping process, chemically digesting fibrous material in a digester while introducing steam into the digester, permitting the steam to condense and mix with the liquor used for digesting purposes, releasing heated mixed liquids and gas from the digester after the liquids have reached a predetermined temperature, circulating the mixed liquids thus released exteriorly of the digester and simultaneously causing the mixed liquids to absorb some of the gas, then returning some of the gas enriched mixed liquids to the digester, and after the mixed liquids reaches a predetermined volume, directing the excess of the mixed liquids into an accumulator.
20. In a chemical pulping process, digesting fibrous material in a digester with chemical liquor while introducing steam into the digester, releasing gas, liquor and steam condensate substantially continuously from the digester after the liquor has reached a predetermined temperature and thereby aiding in maintaining a substantially constant pressure in the digester, permitting an excess proportion of the liquor and steam condensate to accumulate in an equalizing chamber while continuing the digesting, mixing gas from the equalizing chamber with chemical liquor and steam condensate and returning this mixture to the digester during the digestion, and discharging excess mixed liquor and steam condensate from the equalizing chamber after such mixture has reached a predetermined volume.

In testimony whereof, I affix my signature at Watertown, New York, this 19th day of April, 1927.

THOMAS L. DUNBAR.
